UNITED STATES PATENT OFFICE.

EBENEZER EMMET REID, OF BALTIMORE, MARYLAND, AND CHARLES E. BURKE, OF WILMINGTON, DELAWARE, ASSIGNEES TO E. I. DU PONT DE NEMOURS & COMPANY, OF WILMINGTON, DELAWARE, A CORPORATION OF DELAWARE.

PRODUCTION OF ACIDS.

Application filed February 14, 1925. Serial No. 9,089.

This invention relates to the production of acids by the oxidation of hydrocarbons such as occur in paraffin, mineral oils, kerosene, gasoline, and so forth. In the production of such acids the temperature should be kept substantially below 300° C., and preferably not above 200° C., to avoid decomposition, but, at temperatures as low as these, efficient oxidation and conversion into acids is difficult to attain by ordinary methods. We have devised a procedure whereby proper temperatures can be used and yet rapid working and high yields can be attained. It is the major object of the invention to provide a procedure having the desirable characteristics indicated.

The invention comprises as a major feature subjecting the hydrocarbon to an oxygen-containing gas (air) comminuted and disseminated throughout the oil in such an extreme degree of subdivision as to approach molecular dispersion. By proceeding in this way the speed of the reaction at a given temperature is multiplied many times as compared to the speed when the reaction is carried out at the given temperature by ordinary methods. Thus, by the present method desirable temperatures need not be exceeded and yet the manufacturing speed is high, giving practical efficiency.

In practically carrying out the treatment in accordance with the invention we preferably effect the subdivision of the air and its dissemination through the oil by a suitable stirrer driven at such high speeds as to give air bubbles of substantially a size obtainable by introducing the air with a Witt type stirrer of 1½ inches in diameter rotated at a speed of 2000-4000 R. P. M., meaning by a

Witt type stirrer a stirrer of the type exemplified by the stirrer described in Berichte

der Deut. Chem. Gesell., vol. 26, page 1696.

In the accompanying drawing we have shown, without restriction of the invention thereto, a type of stirrer or agitator with which our invention may be advantageously practiced. In the drawing:—Figure 1 is a diametrical vertical sectional view; Figure 2 is a bottom view of the disc or distributor of the agitator shown in Figure 1; and Figure 3 is a bottom view of a simpler form of disc. Referring to the drawing, the agitator comprises a suitable vessel 1, for holding the oil to be treated, the same being

equipped with a liquid inlet 2, vapor outlet 3, draw off pipe 4, and air inlets 5, 5, all suitably valved as indicated. A driving shaft 6 is mounted for rotation in the vessel by the bearings 7 and 8 and this shaft carries the distributor or agitator proper, 9. The distributor 9 is in the character of a disc and, as shown in Figures 1 and 2, may have radial corrugations 10 upon the lower face thereof, or, as shown at 9^a in Figure 3, may have a plain lower face. The ends, 5^a, 5^a, of the air pipes are, as shown in Figure 1, upturned and brought close to the surface of the disc near the centre thereof. If desired, baffles 11, 11 in any convenient number may be provided upon the wall of the vessel, to prevent swirling of the liquid when the distributor 9 is rotated. In operation, the rapidly rotating distributor centrifugally moves the liquid outward from the centre of the disc, giving thorough agitation, and at the same time, the air issuing from the pipes 5, 5, under pressure and close to the centre of distribution of the liquid, bubbles through the liquid, is entrained in the travelling liquid and is centrifugally dispersed through the liquid in a degree of subdivision approaching molecular dispersion. The advisable speed of the stirrer will vary with the size of the disc and the amount of liquid to be agitated. With a corrugated disc we have found that for agitating from 15 to 30 pounds of oil, a disc approximately 3 inches in diameter and operated at 2000 to 4000 R. P. M. is satisfactory. When it is desired to operate under pressure, the air may be introduced at such a pressure, and the relief valve so set, as to give the pressure desired, as will be understood.

The stirrer may be of the form disclosed in United States patent to Thoen No. 641,561 January 16, 1900, or that shown by E. E. Reid, one of the present applicants, in his United States application for patent, Serial No. 482,592, on oxidation of hydrocarbon oils, filed July 5, 1921, wherein the oil is drawn into the stirrer and ejected at high velocity through the body of the oil, entraining air in its passage and mingling the entrained air with the body of the oil.

The temperature at which the reaction is carried out will, of course, vary with the material being oxidized. We prefer to operate at approximately 175° C. when making acids

by the oxidation of paraffin, although we may operate at temperatures approximately between 100° and 250° C. The temperature required depends, in general, upon the 5 activity of the hydrocarbon being oxidized.

In further accordance with our invention, the acids as produced are preferably converted as quickly as possible into metallic salts, whereby they are rendered more stable and excessive decomposition prevented. Thus, we incorporate in the reaction mass, and agitate with the hydrocarbon and air, a dilute solution of sodium hydroxide, sodium carbonate, or some other alkaline solution, 10 that will react with the acids as soon as they are formed, converting them into metallic salts.

When such alkaline aqueous solutions are used in combination with the hydrocarbon 20 and a temperature above that of the boiling point of the aqueous solution is used, it is, of course, necessary to use pressure in order to retain the aqueous solvent in a liquid state. In most cases we have found that 25 only such pressures are necessary as will prevent the volatilization of the water or other volatile products which may be formed during the course of the reaction, say 3 to 215 lbs. per sq. in. gauge with temperature 30 between 100° and 200° C., but higher pressures may be used if desirable.

The process may be illustrated in greater detail by the following example: A convenient quantity of paraffin is placed in a vessel 35 adapted to withstand pressures of 150-200 lbs. per sq. in., together with a dilute solution of caustic soda sufficient to react with the acids which may be formed by the oxidation of the paraffin, the vessel being provided with a stirrer of the type described 40 above. The material is first heated externally until all the solid materials are in the liquid form. Air is then introduced and the stirrer rotated at approximately 3000 R. P. M. and the temperature raised to and 45 maintained at approximately 175° C., and the pressure maintained at about 150 lbs. per sq. in. gauge. During the course of the reaction considerable heat is evolved, and if 50 external heat is used at all after the reaction is well started only enough is used to maintain the reaction mass at the desired temperature. The process is continued until 55 samples of the material indicate that no further oxidation is taking place, at which time the operation is stopped and the reaction mass removed from the vessel.

While the efficiency of the procedure will, of course, vary somewhat with the exact 60 temperature, and other factors, we may state that when carrying out the process as just above indicated, about 60% of the paraffin was oxidized, and of this 60% substantially all was oxidized to fatty acids.

It is to be understood that where we refer 65 in the claims to "hydrocarbon oil" the term is to be taken to include, paraffin, mineral oils, kerosene, gasoline, and the like.

We claim:

1. The method of producing acids by the 70 oxidation of hydrocarbon oil which comprises stirring and distributing the oil at high speed and at a temperature substantially below 300° C. and meanwhile introducing oxygen-containing gas below the surface 75 of the oil and in close relation to the centre of distribution of the oil to thereby effect high dissemination of the gas, and cause the travelling oil to entrain the gas, thereby 80 effecting intimate mixture of the oil and gas; the stirring being at a speed to produce bubbles of substantially the size obtainable by introducing the gas with a Witt-type stirrer of 1½ inches diameter rotated at a speed of 2000 to 4000 R. P. M. 85

2. The method of producing acids by the 90 oxidation of hydrocarbon oil which comprises stirring and distributing the oil at high speed and at a temperature of substantially 175° C. and meanwhile introducing oxygen-containing gas below the surface of the oil and in close relation to the centre of distribution of the oil to thereby effect 95 high dissemination of the gas, and cause the travelling oil to entrain the gas, thereby 100 effecting intimate mixture of the oil and gas; the stirring being at a speed to produce bubbles of substantially the size obtainable by introducing the gas with a Witt-type stirrer of 1½ inches diameter rotated at a speed of 2000 to 4000 R. P. M. 105

3. The method of producing acids by the 110 oxidation of hydrocarbon oil which comprises stirring and distributing a mixture, of the oil and a water solution of an alkali compound of a character to react with the acids as soon as they are formed, to produce salts, at high speed and at a temperature of substantially 175° C. and under a pressure sufficient to substantially prevent vaporization of the water of said solution at said temperature, and meanwhile introducing oxygen-containing gas below the surface of the oil and in close relation to the centre of distribution of the oil to thereby effect high 115 dissemination of the gas, and cause the travelling oil to entrain the gas, thereby effecting intimate mixture of the oil, the solution, and the gas; the stirring being at a speed to produce bubbles of substantially the size obtainable by introducing the gas with a Witt-type stirrer of 1½ inches diameter rotated at a speed of 2000 to 4000 R. P. M. 120

In testimony whereof we affix our signatures.
